UNITED STATES PATENT OFFICE.

LYMAN MELVIN JONES, ANDREW JOHNSTON, AND CHARLES McLEOD, OF TORONTO, CANADA, ASSIGNORS TO MASSEY-HARRIS COMPANY, LIMITED, OF TORONTO, CANADA, A CORPORATION OF CANADA.

SEEDING-MACHINE.

No. 800,215.

Specification of Letters Patent.

Patented Sept. 26, 1905.

Application filed June 18, 1902. Serial No. 112,184.

To all whom it may concern:

Be it known that we, LYMAN MELVIN JONES, ANDREW JOHNSTON, and CHARLES McLEOD, of the city of Toronto, in the county of York, 5 in the Province of Ontario, Canada, have invented certain new and useful Improvements in Seeding-Machines, of which the following is a specification.

Our invention relates to improvements in 10 seeding-machines or drills; and the object of the invention is, first, to provide a readily and easily actuated means whereby the bail to which the drag-bars are connected may be readily raised or lowered so as to raise the 15 drag-bars from the ground or lower such drag-bars and impart any desired pressure to the same; secondly, to devise a support for the end of the pole which will admit of the placing of the gear-wheel centrally behind 20 such pole, and, further, to brace such pole-support to the frame; thirdly, to provide a simple means for throwing the gear-wheel out of mesh when the bail and consequently the drag-bars and hoes are lifted; fourthly, 25 to provide a simple means for throwing the sprocket-driving means of the grass-seed shaft out of gear; fifthly, to provide a readily-adjustable means for varying the pressure of the spring on the pressure-bars; sixthly, to 30 devise a simple means to hold the gate-valve of the feed-run rigidly in the position in which it may be placed either to sow broadcast or in the drills; seventhly, to provide a simple device whereby the turnover gate or 35 plate of the double-feed run may be rigidly and securely held in position; eighthly, to devise an improved and conveniently-located means for actuating the drag-bars, and, ninthly, to devise a central support for the 40 frame whereby the seedbox and the upper portion of the frame may be all removed for shipment without disconnecting or interfering with the drag-bars and their connections to their respective zigzag shafts. To carry 45 out these objects, we have constructed and arranged our machine and the parts thereof in the manner we shall describe hereinafter.

Figure 1 is a perspective view of portion 50 of a seeding-machine or seed-drill, showing the parts involved in our invention. Fig. 2 is an enlarged detail showing our improved lifting mechanism for the bail. Fig. 3 is a detail of the mechanism for adjusting the gear

on the main axle. Fig. 4 is a further detail of such gear-adjusting mechanism. Figs. 5, 55 6, and 7 are details of portion of the gear-adjusting mechanism shown in Figs. 3 and 4. Fig. 8 is a detail of the pole-block. Fig. 9 is a sectional detail of the adjusting device for varying the pressure of the springs on 60 the pressure-bar. Fig. 10 is a perspective detail of the device shown in Fig. 9. Fig. 11 is a detail of the double-feed run, showing the means for securing the turnover-plate in position and for holding the gate directing the 65 grain either to the spout leading to the conductor-tubes or to the spout designed to sow broadcast. Fig. 12 is a detail view.

In the drawings like characters of reference indicate corresponding parts in each figure. 70

A is the seedbox, and B the end castings, one only of which is shown.

C is the bail, the end bars *c* of which are suitably pivoted on the end castings B.

D is a T-shaped angle-bar which extends 75 crosswise of the machine and is securely bolted to the end casting B, as indicated.

E is a bracket which is securely bolted to the cross-bar D substantially centrally.

F is a knee-strut which is securely bolted 80 at the rear to the depending leg *e*, attached to or forming part of the casting E, and at the front end is provided with a notch *f*, extending from the upper edge downwardly. The front end is bent as indicated and is secured 85 by the bolts *f'* to the extension-piece F', which is securely bolted by the bolt *f''* to the front cross-bar of the angle-iron frame 2. The extension-piece F' has a notch *f''*, which extends from the bottom edge upwardly. The two 90 notches *f* and *f''* form a hole, which forms a bearing for the rod G. The other rod H extends through a hole *f''* in the extension-bar F'. The bars G and H are journaled in suitable bearings on the ends of the angle-iron 95 frame 2. Both bars G and H are operatively connected by the quadrants *g* and *h*, which mesh with each other, as indicated.

g' is an arm secured on the end of the bar G, and *g''* is a lever pivoted on the bolt *g'* at the 100 rear of the axle and having the upper end extending above the seedbox. The lower end of the lever *g''* is connected by the link-bar *g''* with the arm *g'*. The upper end of the lever *g''* is provided with a suitable handle, which lies 105 closely to the end of the seedbox, being de-

signed to be held in any desired position by the projecting teeth b . The upper end of the lever g^2 has of course sufficient spring in it so as to enable it to be drawn out from between the 5 teeth, and thus provide for the adjustment of the lever in order to produce the desired movement to the bars G and H, so as to draw the alternate drill-shoes forward or backward, and thus change the angular position of each 10 drill-shoe in relation to the neighboring shoe.

I represents drag-bars which are suitably connected to the bars G and H.

J represents the pressure-bars, which are suitably connected to the drag-bars and extend up through the socket-brackets j , secured to the cross-bar C of the bail in the usual manner.

We do not describe the means of connecting the pressure-bars to the drag-bars, nor do 20 we describe particularly the socket-brackets connected to the bail, as they form no feature in our invention.

K is a spiral spring which encircles the pressure-bar J and is held between the socket-bracket j and the stop L. The stop L is provided with an upwardly-extending portion l , a shoulder l' , intermediate of its length, and a 25 teat l'' , which is designed to extend into a hole k in the pressure-bar. A loop l'' extends from the shoulder around the pressure-bar, as indicated, and is designed to hold the stop on 30 the bar. There are several holes placed in the pressure-bar J, and in order to vary the pressure on the drag-bars it is simply necessary to push up the spring K beyond the upper end of the stop L, whereupon the stop 35 may be swung outwardly away from the bar and the teat l'' inserted into the next hole either above or below, or as may be desired, 40 to produce the desired pressure upon the drag-bars.

The bail C is raised or lowered by the following means: e' is the fulcrum-shaped spindle, which is suitably formed at the end and 45 bolted to the angle-iron cross-bar D. E' is an arm provided at the rear with double bearings e^2 e^3 , intermediate of its length with the quadrant e^3 , and at the forward end with the 50 boss e^4 , through which extends the cross-bar D of the bail. e^5 is a square bar which is round at the ends and journaled at the rear end in the bearing-bracket M and at the front end in a bearing in the bracket E. N is a 55 quadrant gear secured on the bar e^5 and meshing with the quadrant e^3 in the arm E'. M' is a quadrant attached to or forming part of the bearing and provided at each end with the teeth m' and m'' . m^3 is a lever secured at the rear end of the bar e^5 and provided with 60 a suitable plunger m^4 , which is designed to coact with the two sets of teeth of the quadrant. It will be seen by manipulating the lever or throwing the lever in the direction indicated by arrow, so as to engage with the 65 teeth m' , that the quadrant gear N will

throw the arm E', and consequently the bail, downwardly. As the drag-bars also are necessarily thrown downwardly, the depth at which the hoes are inserted will of course depend on the position in which the quadrant 70 is placed in relation to the teeth m' . By throwing the lever in the opposite direction, so as to engage with the teeth m'' , the quadrant N, engaging with the quadrant e^3 , throws the arm E' upwardly, and consequently the 75 bail and drag-bars upwardly, the distance depending, of course, upon the position in which the lever is placed upon the teeth m'' .

It will be noticed that in the means hereinbefore described of raising and lowering 80 the bail the power is applied between the bail and the fulcrum, and as such fulcrum is on a line with the pivot-point of the bail we are enabled to lift the bail with ease and more advantageously than by any means of which 85 we are aware.

O is the pole, which is suitably bolted to the pole-block O'. The pole-block, it will be noticed, is bolted to the cross-bar D by bolts d , is knee shape in form, and provided with a 90 central opening o' , whereby such pole-block is made to straddle the gear-wheel P on the driving-axle 3.

The frame 2 is connected at the rear end to the bearing-casting 4, upon which the seed-box is supported and through bearings in which the axle 3 extends. The bearing-casting 4 is connected at each end by the braces 5 to the cross-bar D. 6 represents diagonally-placed braces, which extend through the sides 100 of the pole-block at one end, being held in place by nuts, and through the bearing-casting 4 at the opposite end, being held in the bearing-casting by a nut, as indicated. The bracing-rods 6 serve to brace the pole-block 105 to the frame.

The gear-wheel P is a face gear-wheel of the usual construction adopted in this class of machine.

Q is a divided sleeve which is secured together through the lugs q by bolts q' . q^2 is a groove formed between the lugs, and q^3 is a step formed on the opposite portion of the divided sleeve, as indicated. The step q^3 forms a bearing for the lower rounded end of the spindle p , which carries the gear-pinion p' , 110 which is driven by the gear-wheel P, so as to rotate the spindle p and drive the feed-run spindle R by a means which it is not necessary here to describe, as it forms no feature 115 in our invention, nor is it necessary for a like reason to describe the radial adjustment of the pinion p' .

The gear-wheel P is held in contact with the gear-pinion p' by means of a spring p^2 , 125 which presses against the hub of the gear-wheel P and against a collar p^3 on the driving-axle 3. The gear of course is secured to the shaft so as to rotate therewith, but is longitudinally adjustable thereon. The sleeve 130

Q, hereinbefore mentioned, is secured to the shaft, and inside of the sleeve next the gear-wheel is located a collar Q', which has an extension-arm q⁴, having a substantially right-angle turn q⁵, such extension-arm q⁴ extending through the groove q².

Q² is a rod suitably secured at one end to the bail C. The other end q⁶ is enlarged and provided with an inclined edge q⁷. It will now be seen that upon the bail being raised, and consequently the rod Q² raised, the collar Q' will be forced lengthwise on the shaft against the tension of the spring p², and consequently throw the gear-wheel in the direction indicated by arrow, and thereby throw such gear-wheel out of mesh with the gear-pinion p'. It will thus be seen that upon every upward adjustment of the bail the gear-wheel and the parts driven by same will be automatically thrown out of gear.

The grass-feed-run shaft R^x is driven from the main axle from a sprocket-pinion R', connected to a suitable sprocket-gear on the grass-seed shaft by a sprocket-chain r. It is of course necessary to provide means for throwing such sprocket-pinion out of and into driving connection with the main axle, and to effect this we provide a toothed clutch r', which is designed to engage with a pin r², extending through the shaft. We also provide a bell-crank r³, which is pivoted on a bolt r⁴ on the cross-bar D and has a forked lower end r⁵, each member of which extends down on each side of the hub of the sprocket-wheel R', as indicated. The opposite end of the bell-crank r³ is provided with a thumb-latch r¹⁰, having an eccentric end, such thumb-latch being pivoted on a pin r⁶, extending through the end of the bell-crank and through the cross-bar D. On the bolt r⁴ we secure a double arm r⁷, one end of which extends up underneath the angle-bar D and the opposite end of which extends down substantially parallel with the lower arm of the bell-crank r³. The lower end of the arm r⁷ is provided with a teat r⁸, and between this teat and a teat r⁹ on the arm extends a spiral spring 7. 8 is a rod connecting the lower arm of the bell-crank r³ to the right-angular projection q⁵ on the end of the arm q⁴. It will now be seen by throwing the thumb-latch r¹⁰ in the direction indicated by arrow that the bell-crank will be tilted on its pivot-bolt r⁴, and thereby throw the sprocket-wheel R' longitudinally on the shaft, so as to throw the toothed collar r' out of engagement with the pin r², extending through the axle 3. At the same time the rod 8 will, by reason of its connection to the arm q⁵ of the collar Q', throw the gear-wheel P out of mesh with the gear-pinion p', connected to the feed-run. It will consequently be seen that both the drives for the feed-run R and the grass-seed shaft R^x are thrown out simultaneously by manipulating the thumb-latch r¹⁰. By throwing the thumb-latch back into the normal position

again it will be seen that the spring 7 will throw the toothed collar r' into engagement with the pin r² again, and consequently the sprocket-wheel R' will be operatively connected to the axle. We can also throw the gear-wheel alone out by hand by means of the arm S, which is journaled on the stud q⁹, forming part of the sleeve Q. The arm S is provided with a cam-shaped end s, which is designed to come in contact with the outwardly-projecting lug Q³, forming part of the collar Q', and by this means when the arm is turned it throws the gear-wheel away from or close to the gear-pinion p'.

In order to hold the turnover gate or plate T in position, we provide the following simple device: The turnover plate T is provided with the end pivot-pins t, attached to or forming part of the same. One end pivot-pin t extends into a notch t' in the side of the hopper. t² is a groove which extends longitudinally of the hopper through the notch t', and t³ is a pin or rod which is placed in the groove t² and extends through the notch t' and over the pin t, and thereby holds the turnover plate securely in place, and yet provides a ready means when the pin or rod t³ is withdrawn to remove the turnover plate.

U represents the wheels of the double-feed run, and V the gate-valve of the feed-run, which is secured on the square rod v and is provided with hubs V', whereby such gate is journaled in the walls.

v' is a lug or stop extending from the side of the feed-run, and v² is a sleeve on the rod v, such sleeve being provided with a projection v³, which is designed to come in contact with one or other of the ends of the lug v', (only one end of which is shown.) The sleeve v² is provided with a handle v⁴ for manipulating it.

v⁵ is a spiral spring surrounding the rod v and extending between the sleeve v² and a collar v⁶ on the shaft. By pressing the handle toward the spring the sleeve may be moved longitudinally, so as to release the lug v³ from the lug v', whereupon the rod v may be turned, by means of the handle, so as to throw the gate V to the reverse side to that shown in Fig. 11. By this means it will be seen that as each chute of the feed-run is designed to throw the grain either broadcast or through the drills that the changing of the gate will serve to direct the grain as desired.

What we claim as our invention is—

1. In a seeding-machine, the combination with the bail and the drag-bars connected to the same, said bail consisting of the pivoted end bars and the cross-bar connecting said end bars and raising and lowering means for said bail interposed between the cross-bar and the line of fulcrum of the bail, substantially as described.

2. In a seeding-machine, the combination with the bail and the drag-bars connected to

the same, of a raising and lowering means interposed between the cross-bar of the bail and the line of the fulcrum thereof and a supporting cross-bar to carry such fulcrum as and 5 for the purpose specified.

3. In a seeding-machine, the combination with the bail and end frame on which the ends of the bail are pivoted and the cross-bar connecting such end frame, of a fulcrum-bar supported on the cross-bar and the arm pivoted 10 on the fulcrum-bar and connected to the cross-bar of the bail and means intermediate of the length of the arm for raising and lowering the bail as and for the purpose specified.

4. In a seeding-machine, the combination with the bail and end frame on which the ends of the bail are pivoted and the cross-bar connecting such end frame, of a fulcrum-bar supported on the cross-bar and the arm pivoted 15 on the fulcrum-bar and connected to the cross-bar of the bail, a toothed quadrant attached to or forming part of the arm and located intermediate of its length, a segmental gear meshing therewith and means for manipulating such gear as and for the purpose specified.

5. In a seeding-machine, the combination with the bail and end frame on which the ends of the bail are pivoted and the cross-bar connecting such end frame, of a fulcrum-bar supported on the cross-bar and the arm pivoted 20 on the fulcrum-bar and connected to the cross-bar of the bail, a toothed quadrant attached to or forming part of the arm and located intermediate of its length, a segmental gear meshing therewith, the shaft on which such gear is secured extending parallel with the ends of the bail, suitable journals for such shaft, a lever secured at the rear end thereof and a notched quadrant with which the plunger 25 of the lever is designed to coact as and for the purpose specified.

6. In a seeding-machine, the combination with the bail pivoted on the ends of the frame, of the cross-bar connecting the ends of the 45 frame, the bracket secured to the cross-bar and having a depending portion, the fulcrum-bar also secured to the cross-bar and to the bracket, the arm journaled on the fulcrum-bar and provided with a toothed quadrant intermediate of its length, the strut extending 50 rearwardly underneath the cross-bar secured to the front portion of the frame and to the depending portion of the bracket, the shaft extending above the strut and journaled at 55 one end on the bracket, the journal-bearing at the rear end of the shaft, the segmental gear secured on the front end of the shaft and meshing with the quadrant on the arm and the lever for manipulating the shaft as and 60 for the purpose specified.

7. In a seeding-machine, the combination with the side portion of the frame and cross-bar and the front U-shaped portion of the frame and the movable bars journaled in the 65 ends of the U-shaped portion, of the strut

supported at the rear end by the cross-bar and extending forwardly of the movable bars and provided with a notch formed in the upper edge thereof, and the extension of the strut suitably bolted to the front of the frame 70 and to the strut, and provided with a hole through which the front movable bar extends, and having a notch extending upwardly from the lower edge through which and the notch in the front end of the strut the rear movable bar extends as and for the purpose specified.

8. In a seeding-machine, the combination with the cross-bar and frame, of the pole-block, knee shape in form, suitably secured 80 to the cross-bar and provided with a central opening designed to straddle the gear-wheel as and for the purpose specified.

9. In a seeding-machine, the combination with the cross-bar and frame, of the pole-block, 85 knee shape in form, suitably secured to the cross-bar and provided with a central opening designed to straddle the gear-wheel and the diagonally-placed braces extending through the sides of the pole-block and through the 90 end portions of the frame as and for the purpose specified.

10. In a seeding-machine, the combination with the bail suitably pivoted on the ends of the frame and means for raising and lowering 95 such bail, of the axle suitably journaled in the ends of the frame and the gear-wheel secured on the axle, a pressure-spring at one end extending between a collar on the axle and the hub of the gear-wheel, the sleeve secured 100 on the axle at the opposite side of the gear-wheel, the gear-pinion journaled in a stud forming part of the sleeve, a collar located between the sleeve and the gear-wheel and provided with an extension-arm and the plunger-rod secured to the cross-rod of the bail and provided with an enlarged lower end extending within the arm and between the sleeve and the collar and having an inclined side as 105 shown as and for the purpose specified.

11. In a seeding-machine, the combination with the bail suitably pivoted on the ends of the frame and means for raising and lowering such bail, of the axle suitably journaled in the ends of the frame, and the gear-wheel 115 secured on the axle, a pressure-spring at one end extending between a collar on the axle and the hub of the gear-wheel, the sleeve secured on the axle at the opposite side of the gear-wheel, the gear-pinion journaled in a 120 stud forming part of the sleeve, a collar located between the sleeve and the gear-wheel and provided with an extension-arm, the arm having a cam-shaped end pivoted on a suitable stud in the sleeve and the coacting projecting 125 lug attached to or forming part of the collar as and for the purpose specified.

12. In a seeding-machine, the combination with the axle and gear-wheel suitably held thereon and designed to rotate therewith, and 130

- a pressure device designed to normally force the gear-wheel in one direction, of the sleeve having a step, the gear-pinion designed to mesh with the gear-wheel and having the shaft thereof journaled in the step, the collar located on the shaft between the sleeve and the gear-wheel and provided with an arm extending through a groove in the connecting-lugs of the sleeve and formed as specified, and means connected to the end of the arm for exerting a pressure on the arm and consequently the collar, so as to throw the gear-wheel out of mesh with the pinion as and for the purpose specified.
15. In a seeding-machine, the combination with the axle and gear-wheel suitably held thereon and designed to rotate therewith, and a pressure device designed to normally force the gear-wheel in one direction, of the sleeve having a step, the gear-pinion designed to mesh with the gear-wheel and having the shaft thereof journaled in the step, the collar located on the shaft between the sleeve and the gear-wheel and provided with an arm extending through a groove in the connecting-lugs of the sleeve and formed as specified, the sprocket-pinion located on the shaft and provided with a clutch connecting the same with the shaft, the bell-crank pivoted on the cross-bar of the frame and having a forked end engaging with the end of the sprocket-wheel and means for operating such bell-crank and a rod connecting the bell-crank to the end of the arm of the collar adjacent to the gear-wheel as and for the purpose specified.
14. In a seeding-machine, the combination with the axle and sprocket-wheel and toothed clutch attached to or forming part of the sprocket-wheel, and a pin extending through
- the axle and designed to normally engage with the toothed clutch, of the bell-crank suitably journaled on the cross-bar of the frame and the thumb-latch provided with a cam-shaped end pivoted on the pin extending through the upper end of the bell-crank and the cross-bar as and for the purpose specified.
15. In a seeding-machine, the combination with the axle and sprocket-wheel and toothed clutch attached to or forming part of the sprocket-wheel, and a pin extending through the axle and designed to normally engage with the toothed clutch, of the bell-crank suitably journaled on the cross-bar of the frame, and means for operating the bell-crank and a double arm located on the pivot-pin of the bell-crank and having the upper portion abutting the cross-bar and the lower portion extending down parallel with the lower arm of the bell-crank and the spiral spring located and exerting a pressure between the arm and the bell-crank as and for the purpose specified.
16. In a seeding-machine, the combination with the bail and the drag-bars, and the pressure-bars provided with holes at their lower ends and suitably connected to the bail, and the drag-bars, of the spiral spring encircling the pressure-bars and the adjustable stop comprising an upwardly-extending portion, a shoulder at the bottom of such portion, a seat designed to engage with the holes in the pressure-bar and a loop straddling the pressure-bar as and for the purpose specified.
